CLAIM

The ornamental design for an eye massager, as shown and described.

DESCRIPTION

FIG. 1 is a front perspective view of an eye massager according to the present invention;

FIG. 2 is a rear perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is a fragmentary cross-sectional view taken in the direction of 9-9 in FIG. 4;

FIG. 10 is an enlarged fragmentary cross-sectional view taken in the direction of 10-10 in FIG. 4;

FIG. 11 is an enlarged view of an area circumscribed in FIG. 1;

FIG. 12 is an enlarged view of an area circumscribed in FIG. 3;

FIG. 13 is an enlarged view of an area circumscribed in FIG. 9;

FIG. 14 is an enlarged view of an area circumscribed in FIG. 10; and,

FIG. 15 is an enlarged view of an area circumscribed in FIG. 10.

The broken lines in FIGS. 1, 3, 11 and 12 are for the purpose of illustrating the environmental structures that form no part of the claimed design. The broken lines in FIGS. 1, 3 and 9-15 depict boundaries of enlargements of an eye massager that form no part of the claimed design. The dot-dash-dot broken lines in FIG. 4 depict the cross-sectional cut lines that form no part of the claimed design.

1 Claim, 15 Drawing Sheets
